COMPOSITE BRIDGE CARD GAME SCORER

Irving Taxel, 74 Howe Court,
Woodmere, N.Y. 11598

Filed Oct. 12, 1965, Ser. No. 87,442

Term of patent 3½ years

(Cl. D34—5)

FIG. 1 is a perspective front view of a composite bridge card game scorer showing my new design with the sliding tabs in operative position; and

FIG. 2 is a perspective rear view of the composite bridge card game scorer.

The characteristic features of my design reside in the combination of the folding double tab indicator and the particular vertical and horizontal arrangements of the window slots, all as shown.

I claim:

The ornamental design for a composite bridge card game scorer, as shown and described.
